UNITED STATES PATENT OFFICE.

ERNEST S. ROE, OF PLYMOUTH, MICHIGAN, ASSIGNOR TO MARKHAM AIR RIFLE COMPANY, OF PLYMOUTH, MICHIGAN, A CORPORATION OF MICHIGAN.

AIR GUN.

Application filed April 20, 1925. Serial No. 24,526.

This invention relates generally to air guns and rifles of the break-down type and consists of certain novel features of constructions, combinations and arrangements 5 of parts as will be more fully described and particularly pointed out in the appended claims.

In the accompanying drawing:

Figure 1 is a side elevation of the gun. 10 Figure 2 is a fragmentary longitudinal section view through a gun embodying my invention.

Figure 3 is a view similar to Figure 2 but showing the stock in open position.

15 Figure 4 is a sectional view taken on the line 4-4 of Figure 2.

Figure 5 is a sectional view taken on the line 5-5 of Figure 2.

20 Figure 6 is a fragmentary perspective view of the channel shaped housing and associated parts.

Figure 7 is a sectional view taken on the line 7-7 of Figure 4.

Referring now to the drawing, the numeral 1 designates a gun embodying my 25 invention having a suitable stock 2 and barrel 3 which are pivotally connected to permit the breaking down of the stock for the purpose of cocking the gun. As shown, 30 the stock 2 is provided at its forward end with the usual casing or housing 4 which normally abuts the rear end of the barrel 3, while the latter is preferably provided at its rear end with a longitudinally extending slot 5 that receives a channel shaped housing 6 for the trigger mechanism. In order 35 that the gun may be readily assembled, the side walls 7 of the housing 6 are preferably slit longitudinally at their forward ends to receive the bottom 8 of the barrel 3 and are pivoted at their rear ends by means of a suitable bolt 9 to the side walls of the casing 4. Any suitable means such as the bolt 9 may be used to connect the walls of the 40 housing 6 to the barrel 3. As shown in Figures 2, 3 and 6 respectively, the side walls 7 of the housing are preferably provided at their forward ends with upstanding lugs 10, which constitute stops or abutments for the 45 rear end of the usual coil spring 11 for projecting the plunger 12 in the barrel 3. This plunger 12 may be any construction desired and is preferably rigidly connected to a 50 rod 13 that extends through the housing

tions of the spring and terminates at its rear 55 end in a suitable hook 14 which is adapted to travel in and be guided by the channel shaped housing 6. Any suitable means such as the U-shaped link 15 may be used to draw the plunger rod 13 rearwardly against 60 the tension of the spring 11 so that the hook 14 will engage a suitable trigger 16 to cock the gun. As shown, the free ends of the link 15 are preferably provided with eyes 17 that receive a bolt 18 extending through the 65 side walls of the casing 4, while the trigger 16 preferably extends through a slot 19 in the base of the housing 6 and is pivoted on a pin 20 extending freely through upstanding lugs 21 on the side walls 7 of the housing 6. As shown in Figure 4 of the drawing, this pin 20 fits loosely in the lugs 21 and will be prevented from becoming accidentally disengaged from the trigger 16 by the side walls 22 of the barrel 3. Thus a smooth 70 shank pin may be used for the pivot and riveting is obviated entirely. Moreover this facilitates greatly the quick assembly of the gun. Any suitable means such as the leaf 75 spring 23 may be used to normally hold the trigger 16 in advanced position against the forward end of the slot 19 in the housing 6. As shown, this spring 23 is return bent 80 through a suitable slot 23' in the trigger and frictionally engages the side walls 7 of the housing 6. Thus this spring will effectively hold the trigger in any adjusted position and will prevent the same from rattling. The trigger 16 is provided at its lower end with a finger opening 25 and is provided on its forward edge with spaced projections 26 and 27 respectively. The upper projection 26 serves as an abutment for the hook 14, while the lower projection 27 is adapted to hold the hook 14 when the gun 85 is cocked. Thus, when the plunger rod 13 is drawn rearwardly by the link 15, the hook 14 will abut the projection 26 and will automatically swing the trigger 16 about its pivot 20 so that the projection 27 will be 90 moved in advance of the lower free end of the hook 14 as shown in Figure 1 of the drawing. The gun will then be cocked.

For holding the stock 2 in its proper relation to the barrel 3 after the breaking down 95 has been effected, I preferably provide an automatic lock which preferably consists of projections 28 which are formed in the sides

of the housing 4 on the stock and which are engageable with suitable recesses 29 in the sides of the channel shaped housing 6 secured to the barrel 3.

5. In use, the stock 2 may be swung downwardly from the position shown in Figure 1 to the position shown in Figure 2 to cock the gun. This movement of the stock will cause the hook 14 of the plunger rod 13 to be drawn rearwardly by the link 15 against the tension of the spring 11 so that the hook will be held by the projection 27 of the trigger 16. The stock 2 may then be returned to normal position, whereupon the 10 projections 28 of the casing 4 will engage the recesses 29 in the housing 6 to hold the parts together. When the parts are in this position, rearward movement of the finger portion 25 of the trigger will release the 15 plunger rod 13.

Thus, from the foregoing description, it will be readily apparent that I have provided a strong and durable gun that is simple in construction. Inasmuch as the housing 6 has a slotted connection with the barrel 3 and the trigger 16 is held in place by a pin 20 that loosely engages the housing 6, it will be also apparent that the parts of the gun may be easily and quickly assembled. Moreover the gun can be manufactured at a comparatively low cost. In addition thereto it will be noted that the housing 6 serves as a neat finish plate for the gun in addition to serving as a housing for the 25 trigger mechanism and a guide for the hook 14 of the plunger rod. Furthermore the forward end of the housing 6 serves as an abutment for the spring 11, hence the usual abutment discs are dispensed with entirely. 30 In other words I accomplish all of the desired results with the use of fewer parts.

While it is believed that from the foregoing description the nature and advantages of the invention will be readily apparent, I desire to have it understood that I do not limit myself to what is herein shown and described, and that such changes may be resorted to when desired as fall within the scope of what is claimed.

50. What I claim as my invention is:

1. In an air gun, the combination with the barrel and stock sections, of a housing for trigger mechanism having a slotted connection with one section and pivotally connected to the other section.

2. In a break down air gun, the combination with separate barrel and stock sections, and a plunger rod in the barrel section, of a connection between said sections including a housing for trigger mechanism having means for guiding the rod.

3. In a break down air gun, the combination with separate barrel and stock sections, of a connection between said sections including a channel shaped housing for trigger

mechanism, and a plunger rod in the barrel having a portion adapted to travel in and be guided by the side walls of said housing.

4. In a break down air gun, the combination with separate barrel and stock sections, of a plunger rod in the barrel section, and a yieldable member for projecting the rod, of a connection between said sections including a housing for trigger mechanism having a portion constituting an abutment for the yieldable member and having a channel portion for guiding the plunger rod.

5. In a break down air gun, the combination with the barrel and stock sections, of a housing for trigger mechanism connected to said sections, a trigger, and a pivot for the trigger extending freely through the housing and held therein by the side walls of the barrel section.

6. In a break down air gun, the combination with the barrel and stock sections, of a channel shaped housing for trigger mechanism terminally connected to the barrel and stock sections and having a slot in the base thereof, a trigger extending through the slot, and a pivot for the trigger extending freely through the side walls of the channel housing.

7. In a break down air gun, the combination with separate barrel and stock sections, of a connection between said sections including a channel shaped housing for trigger mechanism, a plunger rod in the barrel section terminating at its rear end in a hooked portion movable in and guided by the channel housing, and a link connecting said hook portion to said stock section.

8. In a break down air gun, the combination with separate barrel and stock sections, of a connection between said sections including a channel shaped housing for trigger mechanism, a spring projected plunger rod in the barrel section terminating at its rear end in a hooked portion movable in the channel housing, means for retracting the rod against the tension of its spring, and a trigger extending through the base of the housing having a projection for detachably holding the hooked portion of said plunger rod.

9. In an air gun, the combination with the barrel and stock sections, of a housing for trigger mechanism connected to said sections, a trigger carried by the housing, and means for holding the trigger in any adjusted position including an element carried by the trigger frictionally engaging the housing.

10. In an air gun, the combination with the barrel and stock sections, of a channel shaped housing for trigger mechanism connected to said sections, a trigger pivoted between the side walls of the housing, and means for holding the trigger in any adjusted position including a leaf spring car-

ried by the trigger frictionally engaging the side walls of the housing.

11. In an air gun, the combination with the barrel and stock sections, of a housing for trigger mechanism connected to said sections, a trigger pivotally mounted on the housing having spaced projections, and a plunger rod in the barrel section having a hook adapted to abut one of said projections and automatically swing the trigger about its pivot so that the other projection will be moved in advance of the hook.

12. In an air gun, the combination with the barrel and stock sections, of a channel shaped housing for trigger mechanism connected to said sections, a trigger pivoted between the side walls of the housing having spaced projections on its forward edge, and a plunger rod having a hook portion adapted to abut one of said projections and automatically swing the trigger about its pivot so that the other projection will be moved in advance of the hook.

13. In a break-down air gun, the combination with the barrel and stock sections, of a plunger rod in the barrel section opera-

tively connected to the stock section, a yieldable member for projecting said rod, and a housing for a trigger terminally secured to said stock and barrel sections having upstanding lugs constituting stops for the yieldable member and guides for said rod.

14. In a gun of the class described, the combination with the barrel section, of a plunger rod in said section having a hooked portion, and a trigger having an abutment for the hooked portion, and a projection in advance of said abutment for holding said hooked portion.

15. In a gun of the class described, the combination with the barrel and stock sections, of a plunger rod in the barrel section having a hooked portion, a trigger having an abutment for the hooked portion, and a projection in advance of said abutment for holding said hooked portion, and a support for the trigger extending between the stock and barrel sections having means for guiding the hooked portion toward said abutment.

In testimony whereof I affix my signature.
ERNEST S. ROE.
